UNITED STATES PATENT OFFICE

THOMAS S. WARREN, OF HERMOSA BEACH, CALIFORNIA

DESIGN FOR A CASING FOR A HAND MANIPULATED THERAPEUTIC DEVICE

Application filed October 1, 1932. Serial No. 45,190. Term of patent 14 years.

To all whom it may concern:

Be it known that I, THOMAS S. WARREN, a citizen of the United States, residing at Hermosa Beach, in the county of Los Angeles and State of California, have invented a new, original, and ornamental Design for a Casing for a Hand Manipulated Therapeutic Device, of which the following is a specification, reference being had to the accompanying drawing, forming part thereof.

Figure 1 is a top plan view of a casing for a hand manipulated therapeutic device, showing my new design,

Figure 2 is an end view thereof, and
Figure 3 is a front elevation thereof.

I claim:

The ornamental design for a casing for a hand manipulated therapeutic device, as shown.

THOMAS S. WARREN.
